UNITED STATES PATENT OFFICE.

JOHN JOFEH, OF LONDON, ENGLAND.

MACHINE FOR PRINTING FROM STENCILS.

SPECIFICATION forming part of Letters Patent No. 562,898, dated June 30, 1896.

Application filed February 24, 1896. Serial No. 580,555. (No model.) Patented in England April 6, 1895, No. 7,092.

To all whom it may concern:

Be it known that I, JOHN JOFEH, a subject of the Queen of Great Britain, residing at Chingford, London, in the county of Essex, England, have invented a new and useful Machine for Printing from Stencils, (for which I have obtained Letters Patent in Great Britain, No. 7,092, bearing date the 6th day of April, 1895,) of which the following is a full and complete specification.

My invention relates to improvements in machines for printing from stencils, and the object of my invention is to produce a machine which is simple and inexpensive to construct and which will produce copies in a more rapid and reliable manner than those heretofore constructed.

My machine consists of a suitable frame in which slides a carriage to which is pivoted at its lower end the frame carrying the stencil, of a web attached to the lower end of the reciprocating carriage for carrying the sheets of paper and keeping them in contact with the back of the stencil during the downstroke of the frame carrying it. This web also provides a means of lifting the reciprocating carriage.

My invention also consists of devices for separating both the web and the inking-roller from the stencil during its non-printing stroke, and also of a device for insuring the sheet of paper leaving the web at the end of the printing-stroke of the stencil-frame.

In the accompanying drawings, which illustrate my invention, and which form part of this specification, Figure 1, Sheet No. 1, is a view in side elevation. Fig. 2, Sheet No. 1, is a view in front elevation. Figs. 3, 4, and 5, Sheet No. 1, are broken views, on an enlarged scale, showing the device for holding the frame carrying the stencil in a forward position during its up or non-printing stroke. Fig. 6, Sheet No. 2, is a broken view, on an enlarged scale, showing the device for holding the inking-roller clear of the stencil during the non-printing movement of the carriage carrying the stencil. Fig. 7, Sheet No. 2, is a similar view showing the inking-roller in contact with the stencil during the printing movement thereof; and Fig. 8, Sheet No. 2, is a broken view, on an enlarged scale, showing a modification of the said device.

Throughout the views similar parts are marked with like letters of reference.

The stencil-sheet is carried in a suitable frame A, hinged at its lower side in a carriage-frame B, adapted to slide in guides c c, formed on or fixed to the main frame C, the said guides being arranged slightly out of the vertical, so that the stencil-frame A lies by its own weight back in the carriage B, to which it is pivoted at a.

The carriage B is adapted to fall by its own weight and to be lifted by hand through the medium of a web D, attached to its lower end, either directly or indirectly, and passing first over an impression-roller E, carried by the main frame C, and then over a roller E', carried by an auxiliary frame C', pivoted or otherwise attached to the main frame C in close proximity to the rear face of the carriage B. The web D is of a width equal to the width of the frame A, and it is adapted to receive and carry the sheets of paper to be printed on in contact with the back of the stencil. The frame C' is fixed in its position for use by means of a strut, such as c'. As a modification a spring-roller may be substituted for the rear roller E', and the free end of the web D be attached thereto, so that the carriage B would be lifted by its action, in which case the said carriage would be depressed by the pressure of the hand of the operator.

During the down or printing stroke of the carriage B, the rear face of the stencil-frame A—and therefore of the stencil it carries—is in contact with the web D over the impression-roller E, but as the frame reaches the bottom of its stroke the stencil-frame is rocked forward on its pivot a by a cam-piece b, formed or mounted on the stencil-frame A, coming into contact with the roller E or with some convenient part of the main frame C, and it is held in its forward position with respect to the carriage B during the up or non-printing stroke by means of a spring-finger F, pivoted on the carriage B and engaging with a pin or stud b' on the stencil-frame A, the said finger being released automatically when the carriage B has reached the top of its stroke by reason of its curved end f coming into engagement with a projection c' on the frame C.

Pivoted to the top part of the main frame C is a frame G, carrying a transverse axle g , on which is mounted the inking-roller H, and immediately in front of this axle are mounted 5 one or more ink-distributing rollers J, mounted on axles carried by a suitable frame G'. The frame G is so pivoted to the main frame C that the roller H lies by its own weight in contact with the stencil-sheet, but if desired a spring may also be used to increase the pressure. As the carriage B reaches the bottom of its stroke the frame G, carrying the roller H, is rocked on its pivot, to remove the said roller from the face of the 10 stencil, through the medium of a rearwardly-extending arm G^2 and a chain K, or other suitable flexible connection attached to the lower end of the carriage B. The inking-roller H is prevented from coming back into contact with the stencil as the stencil-frame A rises by means of a catch L, pivoted to the main frame A and adapted to engage with a pin or roller l, mounted on the frame G, the 15 said catch being disengaged as the carriage B commences its downward stroke by reason of the engagement with it of a hook m, pivoted to the carriage B, and kept in a position to engage with the said catch L by means of a balance-weight m' or its equivalent.

20 As a modification the catch L may be disengaged as the sliding frame reaches the top of its stroke, in which case a finger M is substituted for the hook m, as shown by Fig. 6.

The paper to be printed on is laid on the 25 web D and is carried in between the rear face of the stencil and the impression-roller E by the travel of the said web, and it drops out automatically when the sliding carriage reaches the bottom of its stroke. To insure that the 30 sheet of paper that has been printed on falls away from the web when the carriage B reaches the bottom of its stroke, the said web is flicked by means of an arm N, formed on one end of a bell-crank lever N' , pivoted to 35 the main frame and adapted to be rocked on its hinge by the carriage B coming into contact with the other end n of the said bell-crank lever as the said frame reaches the bottom of its stroke.

40 Although I have described my machine as printing on the downstroke of the stencil yet it may with equal effect be adapted to print on the upstroke thereof, though the sheets could not be printed so rapidly with a machine so arranged. It will be obvious also that the machine may be operated by power instead of by hand.

I am aware that reciprocating machines for printing from stencils have already been used, 45 and I do not, therefore, broadly claim such as my invention; but

What I do claim, and desire to secure by Letters Patent, is—

1. In a machine for printing from stencils, 50 the combination of a reciprocating carriage, of a frame for carrying the stencil and pivoted to the reciprocating carriage, of an ink-

roller, of an impression-roller, and of a web adapted to carry the sheets of paper and operate the reciprocating frame, all as and for the purpose set forth.

2. In a machine for printing from stencils, in combination, a reciprocating carriage to which is pivoted the frame carrying the stencil, an impression-roller adapted to bear against the rear face of the stencil, an inking-roller adapted to bear against front face of the stencil, and of a web attached to the lower side of the reciprocating carriage and adapted to carry the sheets of paper and to operate the reciprocating frame.

3. In a machine for printing from stencils, in combination, a frame for carrying the stencil-sheet, a reciprocating carriage to which the frame carrying the stencil-sheet is pivoted, an inking-roller located on the one side of the stencil-sheet, an impression-roller located on the other side of the stencil-sheet, a web for lifting the carriage, the device for separating the frame carrying the stencil-sheet from the web during its non-printing movement, and the device for separating the inking-roller from the stencil-sheet during its non-printing movement.

4. In a machine for printing from stencils, in combination, a frame for carrying the stencil-sheet, a reciprocating carriage to which the frame carrying the stencil-sheet is pivoted, an inking-roller located on the one side of the stencil-sheet, an impression-roller located on the other side of the stencil-sheet, a web for lifting the carriage, the device for separating the frame carrying the stencil-sheet from the web during its non-printing movement, the device for separating the inking-roller from the stencil-sheet during its non-printing movement, and the device for flicking the web to insure the sheets of paper falling away from it as the carriage reaches the end of its printing movement.

5. In a machine for printing from stencils, the combination with the main frame C, of the reciprocating carriage B carrying the stencil-frame A, of the auxiliary frame C' carrying the roller E', of the impression-roller E, and of the web D, all as and for the purpose specified.

6. In a machine for printing from stencils, the combination with the frame C of the reciprocating carriage B, of the stencil-frame A pivoted at a to the carriage B and having a cam-piece b, and of the impression-roller E carried by the frame C, all as and for the purpose specified.

7. In a machine for printing from stencils, the combination of the reciprocating carriage B, of the stencil-frame A pivoted at a to the carriage B and having a cam-piece b, and of the spring-finger F pivoted to the carriage B and adapted to engage with a pin or stud b' on the stencil-frame and having its lower end f curved to engage with the projection c² on the main frame C, all as and for the purpose specified.

8. In a machine for printing from stencils, the combination of the main frame C, of the sliding carriage B to which is pivoted the frame A carrying the stencil, of the frame G pivoted to the main frame C and carrying the inking-rollers H and J, of the arm G² forming part of the frame G, and of the flexible connection K between the end of the arm G² and the bottom side of the carriage B, all as and for the purpose specified.
9. In a machine for printing from stencils, the combination of the main frame C, of the sliding carriage B to which is pivoted the frame A carrying the stencil, of the frame G pivoted to the main frame C and carrying the inking-rollers H and J, of the arm G² forming part of the frame G, of the flexible connection K between the end of the arm G² and the bottom side of the carriage B, of the catch L pivoted to the main frame C and adapted to engage with the pin or roller l on the frame G, and of the hook or finger m pivoted to the bottom of the carriage B, all as and for the purpose specified.
10. In a machine for printing from stencils, 25 the combination of a reciprocating carriage B carrying the stencil-frame, of the web D for carrying the sheets of paper, of the impression-roller E, of the inking-roller H, and of the bell-crank lever N' having an arm N 30 formed on its upper end and having its lower end n adapted to come into contact with and be operated by the bottom side of the carriage B as it reaches the end of its printing movement, all as and for the purpose specified.

JOHN JOFEH.
